(57) **CLAIM**

The ornamental design for a guide wire for catheter, as shown and described.

DESCRIPTION

FIG. 1 is a perspective view of the front, right and top of a guide wire for catheter showing our new design;

FIG. 2 is a top plan view thereof, the bottom view being an identical image thereof;

FIG. 3 is a front view thereof, the rear view being a mirror image thereof;

FIG. 4 is a left side view thereof;

FIG. 5 is a right side view thereof;

FIG. 6 is an enlarged cross-sectional view at 6—6 shown in FIG. 3 thereof; and,

FIG. 7 is an enlarged fragmentary view at 7—7 shown in FIG. 3 thereof.

The broken line showing portions of a guide wire for catheter is included for the purpose of illustrating environmental structure and forms no part of the claimed design.

The dashed-dotted line shown in FIG. 7 shows a boundary between the claimed portion and the non-claimed portion.

1 Claim, 3 Drawing Sheets
